UNITED STATES PATENT OFFICE.

WILLIAM KERR, OF PHILADELPHIA, PENNSYLVANIA, ASSIGNOR TO JOHN GAY, OF SAME PLACE.

DESIGN FOR A CARPET-PATTERN.

Specification forming part of Design No. 5,184, dated August 8, 1871.

To all whom it may concern:

Be it known that I, WILLIAM KERR, of the city of Philadelphia and State of Pennsylvania, have invented and produced a new and original Design for Carpet, of which the following is a specification:

The nature of my design is fully represented in the accompanying photographic illustrations, to which reference is made.

I claim as my invention—
The design for a carpet, as shown.
Philadelphia, July 15, 1871.

WILLIAM KERR.

Witnesses:

JAMES H. GAY,
C. QUIRNER.
